TRENCH EXCAVATING MACHINE

William G. Van Voorhis, Columbus, Ohio, assignor to The Jaeger Machine Company, Columbus, Ohio, a corporation of Ohio

Application November 13, 1944, Serial No. 563,125

4 Claims. (Cl. 214—102)

1

This invention relates to ditch and trench-digging machines and has for an object to provide an improved machine for this purpose embodying a portable engine-propelled base vehicle having mounted on one end thereof a turnable mast for effecting the support of a pivotally mounted boom, a ditch or trench-digging scoop or bucket being mounted on the boom for longitudinal travel, there being power-actuated cable means connected with the scoop or bucket for effecting positive advance thereof longitudinally in either direction on the boom.

It is another object of the invention to provide a scoop or bucket for use in connection with such a trench-forming machine which, during its soil-digging or excavating operation, travels from the outer end of its supporting boom toward the automotive base vehicle on which the boom is mounted and wherein the open end of the scoop or bucket is provided with a pivotally mounted door which, through an automatic operation, occupies an open position upon advance movement of the scoop or bucket into the soil and a closed position upon outward movement of the scoop or bucket on the boom, whereby to enable the scoop or bucket to retain soil within the confines thereof during raising of the boom to bring the scoop or bucket to an elevated position of material discharge.

It is a further object of the invention to provide a soil-excavating machine of the character set forth wherein the cable lines, employed in causing the scoop or bucket to travel longitudinally back and forth on its associated supporting boom, are so related to the pivoted door of the scoop or bucket as to automatically open or close the latter when movement of said scoop or bucket on the boom is effected.

Still, a further object of the invention is to provide a loading or excavating machine of this nature characterized by the simplicity of its mechanical construction, the ease by which its operation may be governed, and its compact and sturdy mechanical design by which the same is rendered adaptable for hard usage without liability of mechanical failure.

For a further understanding of the invention, reference is to be had to the following description and the accompanying drawings, wherein:

Fig. 1 is a side elevational view of a loading or excavating machine formed in accordance with the present invention;

Fig. 2 is a top plan view thereof;

Fig. 3 is a front elevational view of the machine, disclosing the boom and scoop in its ele-

vated position at one side of the machine for discharge of the scoop contents into an associated vehicle.

Fig. 4 is a vertical transverse sectional view taken through the boom and scoop on the plane indicated by the line 4—4 of Fig. 1;

Fig. 5 is a horizontal sectional view on the plane indicated by the line 5—5 of Fig. 1;

Fig. 6 is a detail sectional view disclosing the pivotal connection between the scoop and its associated carriage and the door-operating yoke, the plane of the figure being disclosed by the line 6—6 of Fig. 3;

Fig. 7 is an enlarged fragmentary top plan view of the boom and its supporting mast;

Fig. 8 is a fragmentary side elevational view disclosing the cable-operated scoop or bucket at the outer end of the supporting boom and in a trench-digging position.

20 Referring more particularly to the drawings, the numeral 10 designates the chassis or frame of an automotive base vehicle, which forms a part of my improved loading or excavating machine; the numeral 11 designates the material-handling excavating scoop, shovel or other load carrier; the numeral 12 designates generally the boom employed in the raising or lowering of the scoop to cause it to assume desired positions of material excavation and discharge, and the numeral 13 designates in its entirety a vehicle-carried mast to which the boom is pivotally united at its inner end for turning movement about both horizontal and vertical axes.

The mast is carried by the frame 10 at its forward or loading end and is disposed over a pair of ground-engaging power-driven traction wheels 14. Mounted on the frame 10 is a power plant 15 which, conveniently, is in the form of an internal combustion engine having associated therewith a change-speed transmission 16 and suitable drive connections adapted to impart power to the wheels 14. The end of the frame 10 opposite to the wheels 14 is provided with one or more ground-engaging steering wheels, not shown, which may be manipulated by the customary steering control 17 located conveniently to the operator's position 18.

The mast includes a tubular column 19, which is rotatably supported at its lower end in connection with bearings provided on the frame 10, and at its upper end in a bearing 20 projecting from the machinery-confining housing 21 of said frame. The bottom of the column has fixed thereto a worm gear segment 22, the teeth of which mesh with an engine-driven worm 23 and

by means of which the column may be rotated about its vertical axis. Formed with and arising from the segment 22 are ears 24 to which are pivoted for turning movement about a horizontal axis the inner ends of a pair of boom rails 25, the latter being disposed on opposite sides of an inverted U-shaped beam 26, the rails 25 being of channel-form to provide open-sided guides. The rails 25 and the beam 26 are rigidly united in spaced order by transverse bars 27 to form the complete boom.

Mounted for longitudinal travel in the guides provided by the rails 25 are rollers 28, the latter being mounted for rotation on inwardly projecting studs 28a carried by a pair of carriage plates 29. The lower edges of these plates are pivotally united as at 30 with the vertical sides 31 of said scoop. The scoop or bucket is closed on all sides except the open front thereof, and when the scoop is moved upwardly with the boom to a discharge position, as in Fig. 3, the open end thereof is closed by a pivotally mounted door or end closure 34, the latter having its upper portion pivotally mounted as at 35 in connection with the top of the scoop.

The door 34 is normally held in its scoop-closing position by providing the sides of the scoop with a pair of pivoted bolts 36. The threaded free ends of these bolts receive nuts 37 against which press the outer ends of a pair of coil springs 38, the opposite ends of the latter being engaged with turnable heads 39 carried by the side edges of the door 34, the expansive force of said springs thus serving to hold the door in its position of scoop closure.

The pivotal connections 30 between the carriage plates 29 and the scoop sides 31 include turnable studs 40 having headed outer ends 41. The heads 41 are formed with openings for the sliding reception of a door-operating yoke 42, the intermediate portion 43 of this yoke being received within ears 44 projecting from the door 34. When the door is open, by means hereinafter described, it will be seen that the springs 38 are compressed and the yoke 42 slides outwardly in the heads 41. When the forces opening the door are released, the expansion of the springs 38 forces the door to its position of scoop closure in order to confine the contents thereof, and the yoke slides forwardly in the openings provided in the stud heads 41.

Connected with the intermediate portion of the yoke 42 is one end of a cable 45. From its point of connection with the yoke, the cable 45 extends to a sheave 46 carried by the inner ends of the boom rails 25. From the sheave 46, the cable 45 is trained upwardly, passing over a sheave 47 mounted on the upper end of the mast 13. After passing over the sheave 47, the cable 45 depends vertically through the hollow interior of the column 19 and, at the lower end of the column, passes around a sheave 48 supported on the vehicle frame 10. From the sheave 48, the cable 45 extends to a power-actuated drum 49 driven by the engine 15 and mounted on the frame 10.

It will be seen that when the cable 45 is wound about the drum 49 so that its effective length is shortened, the first movement of said cable causes the scoop door to swing to an open position against the resistance of the coil springs 38, the opening movement of the door being limited by the contacting of stop enlargements 50 provided on the ends of the side legs of the yoke 42 with the heads 41 of the studs 40. When this occurs, a direct pull is imparted by the cable 45 to the carriage

29, thereby causing penetration of the scoop into the soil and movement of the scoop longitudinally and inwardly of the boom toward the base vehicle 10.

5 When the scoop is filled with soil, or other material being gathered or excavated, rotation of the drum 49 is discontinued, and by customary clutch and brake control on the drum 49, the tension on the cable 45 may be released, thereby 10 causing the door 34 to assume its position of scoop closure as a result of the expansion of the springs 38. The boom is then oscillated about its horizontal axis, provided by the ears 24, whereby to cause elevation of the scoop from the 15 ground or other working surface and after which the scoop, with its open end closed by the door 34, is moved linearly and outwardly of the boom to a discharge position. Such outward movement of the scoop is effected by a cable 51, which is fastened at one end, as at 52, to the carriage 29. From its point of securement to the carriage, the cable is advanced forwardly of the boom and trained over a sheave 53 fixed for rotation on the outer end of said boom.

25 From the sheave 53, the cable 51 is trained rearwardly, passing around one of the sheaves 46 at the inner pivoted end of the boom. From the sheave 46, the cable 51 passes upwardly in parallel order with the cable 45 and is trained around one of the sheaves 47, then passing downwardly through the column 19, around one of the sheaves 48 and is then wrapped around a drum 54 to which its inner end is secured. The drum 54 is disposed on the frame 10 adjacent to the drum 49, both drums through suitable clutch and brake controls being actuated by power derived from the engine 15. Thus with the drum 49 released to permit of the withdrawal of the cable 45 therefrom, the rotation of the drum 54 40 will cause the cable 51 to be wound thereabout shortening the effective length of said cable and causing the carriage and scoop to be moved outwardly and linearly of the boom 25.

To raise the boom so that the scoop, when advanced to the outer end of said boom, will occupy an elevated position, for instance, above the body 55 of a dump truck, use is made of a third cable 56. This cable has its inner end anchored to a bail 57 which is pivoted as at 58 on the upper 50 end of the turnable mast 13. From its point of connection with the bail 57, the cable 56 extends to a sheave 59 mounted on the extreme outer end of the boom structure. After passing around the sheave 59, the cable 56 is trained rearwardly, 55 passing over the sheave 47, thence downwardly through the column 19, around the sheave 48 and is wrapped around and secured to a third drum 60. This latter drum is mounted on the vehicle frame 10 adjacent to the drums 49 and 54 and 60 like the latter drums is operated by motion transmitting means 61 from the engine 15, the drum 60 having the usual individual brake and clutch controls of standard design. When the cable is wrapped around the drum 60, it will be seen that 65 forces are applied to the outer end of the boom structure, causing the latter to swing about its horizontal pivotal connection 24 in an upward direction until elevated to the full line position disclosed in Fig. 3.

70 With the boom held in such an elevated position, the cable 45 is actuated to open the door 34, providing for gravitational discharge of the scoop contents into the vehicle body shown at 55, or other elevated receiver. Preferably, the outer 75 ends of the boom rails 25 are, as viewed in Fig. 1,

inclined upwardly as at 62, so that when the boom is elevated and the scoop advanced into registration with the inclined region 62 thereof, the scoop will assume an enhanced position of angularity to insure complete gravitational outflow of its contents.

It is often desirable in the operation of a machine of this character to swing the boom and scoop so that the same will be positioned laterally to one side or the other of the portable base vehicle. Thus in a trench-forming operation, the dump vehicles which are used to convey the excavated soil from the trench site, are driven to occupy positions parallel with the base vehicle, as shown in Fig. 3. Hence, to discharge the contents of the scoop into the body of a dump vehicle so positioned, it is necessary to swing the boom and scoop laterally of the machine so that the same will occupy the positions depicted in Fig. 3.

In the present machine, this may be conveniently accomplished by turning the column 19 about its vertical axis, which swings with it the boom structure and scoop. Through the motion transmitting means 61 and reversing clutches 63, power from the engine 15 is applied to the worm 23 to rotate the latter in one direction or the other, thus turning the segment 22 and the column 19 therewith, producing required horizontal swinging movement of the boom and scoop in the direction desired.

In view of the foregoing, it will be seen that the present invention provides an excavating or loading machine for use in many capacities when earth and other loose bulk materials of various kinds are required to be removed from the ground, or other base surface, and elevated to a desired position of discharge and deposit. A particular advantage which the machine possesses is found in constructing and mounting the boom so that, in addition to lifting the associated scoop in a vertical direction, it may also be revolved about a substantially vertical axis to locate the scoop laterally of the machine. This feature provides for greater facility in operation by reducing the amount of maneuvering of the automotive base vehicle to effect registration of the scoop with associated drum vehicles or other positions of material deposit. The power driven mechanism for turning the mast and boom structures is so constructed that it locks the latter against undue horizontal swinging movement by the use of worm gearing. Also, the machine is further characterized by its mechanical simplicity and ability to receive and handle heavy loads expeditiously with complete and convenient control thereover. The opening and closing of the scoop door 34 is controlled automatically by the employment of the cables 45 and 51 and the springs 38, thereby avoiding the employment of latch devices and associated manual controls.

The scoop door may be opened by four different methods. First, by pulling on cable 45 while the bucket is making a cut, the required cutting force supplying the reaction needed to overcome the tension of the spring 38, as in a typical trench-digging operation; second, by pulling on cable 51 and holding stationary the cable 45, as in dumping the bucket or scoop; third, by pulling on cable 45 and holding stationary cable 51, as at the start of a trench-digging cut; fourth, by pulling on cables 45 and 51. This method may or may not be used and its only purpose would be to open the door 34 in the least possible time. The angular outer end of the boom not only is advan-

tageous in the dumping of the scoop or bucket 11, as illustrated in Fig. 3, but it is also equally advantageous in starting a trench-digging cut, as shown in Fig. 8.

It will be understood that certain changes may be made in the construction of my improved machine without departing necessarily from the spirit and scope of the following claims.

I claim.

1. In a material excavating and loading machine, a portable base vehicle, a mast mounted on said base vehicle and turnable about its longitudinal axis, a pivot at one end to said mast beam for raising and lowering movement in vertical planes and swinging movement in horizontal planes, a scoop suspended from said boom and movable longitudinally thereof toward and away from said base vehicle, said scoop being openable at the front end thereof to provide for the admittance of excavated materials therein and the discharge of such materials therefrom, a door hinged to said scoop and normally closing the front end thereof, bolts pivoted to the sides of said scoop, turnable bearing elements carried by said door for the slidable reception of said bolts, coil springs confined between the outer ends of said bolts and said turnable bearing elements, said springs normally serving to maintain said door in its position of scoop closure, yoke means connected with said door and said scoop for limiting the opening movement of said door, and a pair of drum-actuated cables carried by said base vehicle, one of said cables being connected with said door and the other of said cables with said scoop, whereby to effect automatic actuation of said door and the movement of said scoop longitudinally of said boom toward and away from said base vehicle.
2. In a loading machine, a portable self propelled base vehicle, a turnable mast structure carried by and arising from said base vehicle, a boom having its inner end pivotally connected with said mast structure for swinging movement in vertical planes, said boom projecting beyond one end of said base vehicle and being turnable in unison horizontally with said mast structure, a carriage movable longitudinally of said boom, a scoop supported by said carriage, said scoop being closed on all sides and having an openable front end facing toward said base vehicle, a movable door carried by said scoop and normally closing its open front end, yieldable means normally serving to maintain said door in its position of scoop closure, means for limiting the opening movement of said door, power-actuated means mounted on said base vehicle, and a pair of operating cables cooperative with said drum means for effecting longitudinal movement of said scoop along said boom, one of said cables being connected with said carriage to move said scoop in an outward direction along said boom and the other of said cables being connected with said door to move said scoop inwardly along said boom in a material-gathering direction, said last-named cable serving also to effect the opening of said door as desired.
3. In a loading machine, a portable base vehicle, a vertical mast carried by and arising from said vehicle, a boom structure pivotally mounted on said mast for movement in vertical planes and lateral swinging movement, said boom structure being formed with longitudinally extending guides and an upwardly inclined outer end, a scoop carriage having roller elements longitudinally movable in said guides, a scoop secured to said carriage for pivotal adjustment relative thereto, said

scoop having an open front end and closed side, back, top and bottom walls, a swinging closure for the open front end of said scoop, spring means normally serving to maintain said closure in a position closing the open front end of the scoop, a slideable yoke connected with said carriage and said closure for limiting opening movement of the latter, and a pair of drum actuated cables for moving said scoop longitudinally of the boom structure, one of said cables being connected with said carriage and trained toward the outer end of said boom and the other of said cables being connected with said yoke and trained toward the inner end of said boom.

4. In an excavating and loading machine, an 15 elongated vertically movable boom formed with a guideway, a scoop carriage depending from said boom and supported for movement longitudinally in said guideway, a scoop having an open front, means pivotally uniting the sides of said scoop with said carriage to control the cutting angle of the scoop, said means including turnable

5 studs, a door pivoted to the top of said scoop and movable in a vertical plane to open and close the front thereof, a bail having side legs slideable in openings formed in said studs, said bail having a cross leg uniting the side legs thereof, the cross leg being pivotally joined with said door, pivotally movable spring means united with said scoop and door and effective when released to maintain the door in a position closing the front 10 end of said scoop, cable means connected with the carriage of said scoop and trained over guides carried by the outer end of said boom for positively moving said scoop in one direction longitudinally with respect to the boom, and additional cable means extending over guides disposed adjacent to the inner end of said boom and connected with said door to open and close the latter against the resistance of said spring means and to advance 20 said scoop longitudinally of said boom in a direction opposite to that afforded by said first-named cable means.

WILLIAM G. VAN VOORHIS.
